OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

RIBBON-VIBRATING MECHANISM.

1,256,077.

Specification of Letters Patent. Patented Feb. 12, 1918.

Application filed May 18, 1917. Serial No. 169,583.

To all whom it may concern:

Be it known that I, OTTO THIEME, a citizen of the United States, residing at the city of St. Louis, State of Missouri, have 5 invented a certain new and useful Improvement in Ribbon-Vibrating Mechanism, of which the following is a full, clear, and exact description, such as will enable others skilled in the art to which it appertains to make and 10 use the same, reference being had to the accompanying drawings, forming part of this specification.

This invention relates generally to writing machines, and specifically to a ribbon 15 vibrating mechanism for such machines.

The general object of my invention is to provide an improved ribbon vibrating mechanism designed for a visible or front strike machine and arranged for operation in conjunction with type bar mechanism of a sort 20 commonly employed in type bar machines, and also with number listing mechanism of a type employed in a computing machine of the sort disclosed in my copending application, Serial Number 112,584, filed August 1, 1916.

The machine is designed so that a single ribbon will be used in common by both the printing mechanism of the computing machine and the printing mechanism of the typewriting machine. Provision, therefore, is made for vibration of the ribbon to and from the printing line upon the printing 30 operation of either mechanism, and a means for changing the ribbon vibrating operation so that the printing may be done selectively from either color zone of a bichrome ribbon.

In the accompanying drawings, I have shown for the purpose of illustrating my invention, one embodiment thereof—

Figure 1 being a perspective view of the same;

Fig. 2 a detail of a fragmentary front view showing association of the ribbon vibrators and the printing devices;

Fig. 3 a view in the nature of a longitudinal vertical section through the machine showing various of the parts in elevation and others in sectional elevation.

Referring first to Fig. 3, it will be observed that spool shafts 90 are journaled in brackets 91, one at each side of the machine, said shafts being vertically disposed and having their upper extremities extending 55 above the cover plate of the machine, where

they support the spools 94 at a level slightly below the printing line. The ribbon 95 passes from one spool to the other along the front of the paper carriage just below the printing line, being operatively engaged by 60 vibrating guides 96, one at each side of the printing area. These vibrating guides are carried on slideways 97 which are supported on the frame cover plate, the connection being such that the guides have vertical sliding movement thereon. Depending bracket members 98 afford supports for the pivotal mounting of the vibrating levers 99 and 99'; the former having slot and pin connection with the left hand vibrating guide 96, and 65 the latter having slot and pin connection with the right hand guide 96. The mounting of the vibrating levers on the brackets 98 is also by means of a slot and pin connection, so that the levers may be shifted longitudinally with reference to the brackets and the vibrating guides. The fulcrum pin y of the lever 99 is carried on a longitudinally movable link 100, while the fulcrum pin y' of the vibrating lever 99' is carried on a 70 longitudinally shiftable link 101. A cam plate 102 is longitudinally shiftable by operation of the ribbon shift key which is disposed in the keyboard, the lever of which is shown at 104, and which is connected by a 75 link 105 to a bell lever 106 pivoted at 106a and having its other arm connected to the cam plate 102. The cam plate is provided with a diagonally inclined cam slot 107 in which operates a pin 108 carried by shiftable link 100. Cam plate 102 has a second diagonally inclined cam slot 109 in which 80 operates a pin 110 carried by shiftable link 101. Longitudinal movement of cam plate 102 upon operation of ribbon shift key lever 85 104, will move shiftable links 100 and 101 longitudinally so as to shorten the power arms of vibrating levers 99 and 99'. The power arm of vibrating lever 99 is under control of a crank 111 carried on a shaft 112 90 100 which is rocked by a connecting rod 114. Similarly the power arm of vibrating arm 99' is controlled by crank 115 carried on a shaft 116 which is rocked by the connecting rod 117.

In Fig. 3, I have shown in dot and dash lines elevational outlines of the typewriter printing bars, which are designated by the numeral 16, and of the type bars of the computing mechanism which are designated by 110

the numeral X³⁶. Both are shown in their retracted or inoperative positions, and it will be understood that as actuated, they will be moved into effective coöperation with the 5 ribbon at the front of the platen.

In Fig. 2, I have shown in dot and dash outline the location of the type carrying members of the computing machine, and also the type bar guide 73 which stands below 10 and at the position of the printing point of the typewriting mechanism.

Referring to Figs. 1 and 3, it will be observed that connecting rods 114 and 117 are actuated for longitudinal reciprocation by 15 movement of a sleeve 118, to which connecting rods 114 and 117 are connected respectively by crank arms 119 and 120. This sleeve 118 is arranged to be rocked on its axis by virtue of its connection through 20 crank arm 121, and link 122 with print control lever X⁴⁹ of the computing machine. By virtue of the connections as described in my copending application above referred to, this print control lever X⁴⁹ governs the 25 operation of the printing hammers which effect the printing from the number type of the computing machine. For the purpose of the present explanation, it is sufficient to state that this print control lever X⁴⁹, which is 30 pivoted at X⁵⁰, and held under tension by the spring X⁵², is rocked by the influence of said spring at every printing operation of the computing machine. It will be seen that in 35 this rocking operation the lower end of lever X⁴⁹ is swung rearwardly, or to the left, as illustrated in Fig. 3. At such times as no printing is to be effected from the computing machine number types, as when items are simply accumulated and not listed, this 40 lever remains stationary. As a consequence, upon every printing operation of the computing mechanism, sleeve 118 will be rocked, and, by virtue of the operating connections just above described, both of the vibrating 45 guides 96 will be raised to carry the ribbon to the printing line to receive the impact of the type. This raising of a considerably longer extent of the ribbon is necessary when the computing machine printing mechanism 50 is operated, by virtue of the fact that the printing members of the computing machine comprehend a considerable longitudinal extent of the ribbon, the extent depending, of course, upon the number of denominational 55 orders for which the machine is equipped. In the operation of the typewriting mechanism, however, raising of this considerable extent of ribbon is not necessary, as but a single letter is printed at a time, nor is the 60 raising of this considerable extent of ribbon desirable in the operation of the typewriter, for the reason that it would make the operating touch heavier. Accordingly, the vibration of the ribbon upon operation of the 65 typewriting mechanism is accomplished

through the instrumentality of the connection between shaft 116 and rock shaft 68 formed by crank 124, thrust link 125 and arm 126. It will be recalled that the rock shaft 68 is rocked through its connection with the universal bar 112 upon operation of any type bar, and, as shaft 116 is effective only upon vibrating lever 99, only the right hand vibrating guide 96 will be raised upon operation of the typewriter printing mechanism. As will be seen in Fig. 2, the printing point of the typewriting mechanism is adjacent to the right hand vibrating guide 96, so that the movement of the single guide elevates enough of the ribbon to effect the 80 printing from the type bar.

I have explained above how the power arms of levers 99 and 99' are shortened by the shifting of cam plate 102. Inasmuch as the arc of movement of cranks 111 and 115 is always the same, a shortening of the power arms on the vibrating levers will result in their weight arms being given an increased extent of movement. Hence, when printing from the upper zone of a 90 bichrome ribbon, the levers 99 and 99' will be in the positions illustrated in Fig. 1, whereas when it is desired to print from the lower-color zone of a bichrome ribbon, said levers will be shifted outwardly as above 95 described and the vibrating guides 96, as a consequence, will be given a greater extent of vertical movement so as to bring the lower zone of the ribbon over the printing line in the vibrating operation. By virtue of this 100 mechanism, a single item may be printed in red by simply holding down the key lever 104 pending the operation of the number printing mechanism, and upon the release of the ribbon shifting key, the parts will 105 be restored to normal position for the printing in the customary color by the reaction of spring 104' which is placed under tension when the key lever 104 is depressed. For the purpose of enabling printing in red from 110 the type bars, any suitable locking device may be employed for holding key lever 104 depressed.

I am aware that the mechanism herein illustrated and described is susceptible of 115 various changes, modifications and adaptations not specifically referred to, but comprehended nevertheless within the spirit of my invention and the scope of the following claims.

What I claim is:

1. In a typewriter, a ribbon-vibrating mechanism including vertically movable ribbon guides, a lever operably connected with each guide, a rock shaft associated with each 125 lever, means for operating the rock shafts to swing the levers, and key-operated means for varying the length of the power arms of the said levers for the purpose described.

2. In a typewriter, a ribbon-vibrating 130

mechanism including a pair of independently movable ribbon guides, a lever for vibrating each guide, a crank member for swinging each lever, means for actuating both of said crank members in unison, and means for actuating one of said crank members independently of the other.

3. In a typewriting machine, a ribbon-vibrating mechanism including a ribbon guide, a lever for vibrating the guide, a crank for swinging the lever, means for actuating the crank, a shiftable plate upon which the lever is fulcrumed, and means for shifting the plate to vary the operative relationship of the crank and the lever.

4. In a writing machine, the combination of manually operable printing mechanism, number printing mechanism operable separately therefrom, a ribbon coöoperating with said printing mechanism, friskets for guiding said ribbon, means operable from the manually operable printing mechanism for operating one of said friskets to move the ribbon for coöperation with the manually operable printing mechanism, and means operated with the mechanically operable number printing mechanism to operate a plurality of the friskets.

5. In a writing machine, the combination of type-carrying members separately operable and arranged to print respectively at different points, a ribbon arranged to serve said type-carrying members, friskets for handling said ribbon, an independently operable lever associated with each frisket, means associated with one of said type-carrying members for operating one of said

levers, and means operably associated with the other of said type-carrying members for operating both of said levers.

6. In a writing machine, the combination of independently operable type-carrying members arranged to print respectively at different points, a ribbon arranged to serve both of said printing members, friskets arranged to guide said ribbon, means operable with one of said printing members to operate one of said friskets, and means operable with the other of said printing members to operate two of said friskets.

7. In a writing machine, the combination of independently operable type-carrying members arranged to print respectively at different points, a ribbon arranged to serve both of said printing members, friskets arranged to guide said ribbon, means operable with one of said printing members to operate one of said friskets, and means associated with the other of said printing members to operate the other of said friskets.

8. In a writing machine, the combination of independently operable type-carrying members arranged to print respectively at different printing points, a ribbon disposed to serve both of said type-carrying members, guides for said ribbon, means for vibrating said ribbon for coöperation with both of said type-carrying members, and means for vibrating said ribbon for coöperation with one of said type-carrying members exclusive of the other.

In testimony whereof I hereunto affix my signature this 10th day of May, 1917.

OTTO THIEME.
